UNITED STATES PATENT OFFICE.

PHILIP BRUNER, OF BOISE, IDAHO.

HEEL-REMOVING MACHINE.

1,226,460.

Specification of Letters Patent. Patented May 15, 1917.

Application filed September 5, 1916. Serial No. 118,537.

To all whom it may concern:

Be it known that I, PHILIP BRUNER, a citizen of the United States, residing at Boise, in the county of Ada and State of Idaho, have invented certain new and useful Improvements in Heel-Removing Machines; and I do hereby declare the following to be a full, clear, and exact description of the invention, such as will enable others skilled in the art to which it appertains to make and use the same.

My invention relates to heel removing machines and is designed particularly for cutting off the heels of boots or shoes ready for being replaced by the new heel of leather or rubber as desired.

The object of my invention is to make a clean, clear cut through the heel in such a manner as to leave any desired portion of the old heel remaining in a true level condition for the reception of the new heel to be placed thereon.

A further object of my invention is to insure that no part of the heel or shoe will be touched by the machine except where the knife does its work of cutting through the heel either between any of the layers of leather forming the heel or the knives may be directed to cut directly through one of the layers of leather if so desired.

Other objects and advantages will be hereinafter set forth in the following specification taken in connection with the accompanying drawings which are made a part of this application and in which,

Figure 1 shows my hand controlled machine complete ready for use.

Fig. 2 shows a reverse side of the machine shown in Fig. 1.

Fig. 3 is a sectional view of the knife guides and showing a section of one of the knives.

Fig. 4 shows one form of foot controlled machine, while

Fig. 5 shows another form of foot controlled machine wherein both the upper and lower knives are operated.

In order to conveniently refer to the various parts of my invention and coöperation accessories, numerals will be employed, the same number applying to a corresponding part throughout the several views.

In materializing my invention I provide a suitable base 1 of any preferred construction upon which I erect the supporting standards 2 in any desired manner in which

a stationary knife 3 is mounted and a movable knife 4 is also arranged, though it is obvious that both knives may be made movable as shown in Fig. 5 of the drawings. 60 The cutting standards 2 are more clearly shown in Fig. 3 of the drawings wherein it will be observed that each guide on its inner side is provided with a groove to receive the stationary or movable knife members as the case may be. 65

The upper ends of the standards are connected together in any suitable manner as by the cross bar 5 or equivalent means. The lower movable knife is provided with a shank or stem 6 which may be formed upon one or both edges with a rack bar or teeth 7 designed to coöperate with the controlling pinion 8 to which is secured the lever or crank member 9 whereby the knife may 70 be readily raised or lowered incident to the use of the machine. The movable knife 4, therefore, may be caused to coöperate with the stationary knife 3 in the manner above described. 75

In Fig. 5 I have shown that the upper knife 3 may be made movable so that it can be raised and lowered in the guiding members 2 by means of the controlling arm or bar 10 which is provided on its upper edge 80 with a plurality of teeth 11, thereby forming it into a cog bar designed to coöperate with the pinion 12 mounted in any suitable manner as upon the axle or shaft 13 properly journaled and held in place by an extension 14 of the standards 2 or equivalent means. 85

The pinion 12 is also placed in mesh with the teeth 15 upon the contiguous side of the rack bar 6, and since the rack bar 6 is also provided with teeth on its opposite edge as 90 before stated the said bar is thus disposed in coöperation with the pinion 8. 95

In order to control the lower cutting blade by foot power I provide a controlling bar or rod 16 suitably mounted in a vertical position upon the standard 2 and having upon its lower end a suitable pedal or member 17 to be engaged by the foot of the operator and it follows that when the bar 16 is thus forced downward by the foot 100 of the operator it will cause the upper and lower knife to be moved simultaneously toward each other and when the foot pressure is removed the compression spring 18 will cause the bar 16 to be elevated and incidentally raise the upper blade and depress the lower blade, thus leaving the cutting 105 110

blades normally separated from each other ready for the reception of the next heel to be removed.

It will be readily understood that the bar 5 16 is to be mounted so that it can have a free longitudinal movement and thereby operate the pinion 8 causing said pinion to act upon the rack bar or shank 6 of the knife 4 and it is obvious that when the rack bar 6 10 is thus forced upward it will act upon the pinion 12 in such a manner as to cause the rack bar 10 to be moved downward bringing with it the upper knife 3 properly mounted for that purpose.

15 If preferred the foot controlling bar or rod 16 may be employed to act upon the lower knife only, in which case the upper knife is made stationary and the tooth bar 10 may be wholly dispensed with. The compression spring 18 will obviously restore the 20 lower blade to its normally lowered position ready for acting upon the next heel.

Obviously the various elements of my invention may be made in any desired manner and properly assembled as shown, 25 whereby a reliably efficient heel removing machine is formed so that the heel of a boot or shoe may be very quickly and cleanly cut away including the clean severance of all 30 nails, pegs or the like, thus leaving the remaining portion of the heel in a true cleanly cut condition ready for the reception of the new heel to be added.

It will be found in practice that my heel 35 removing machine will thus reliably perform its office and will result in a great saving of both time and labor in the work of removing old heels and preparing for their replacement with new heels of leather or 40 rubber as preferred.

While I have described the preferred combination and construction of parts deemed necessary in materializing my invention I 45 wish to comprehend in this application all substantial equivalents and substitutes

which may be considered as falling fairly in the scope of my invention.

Having thus described my invention what I claim and desire to secure by Letters-Patent is:—

1. A heel removing machine comprising a base, supporting standards projecting upwardly from the base, a pair of knives vertically movable in said standards, a rack bar depending from the upper knife, a shank 55 projecting from the lower knife and provided in its opposite side edges with rack teeth, a pinion disposed between said shank and rack bar, another pinion meshing with the opposite side edge of the shank, and means 60 for rotating said last-named pinion to cause said knives to reciprocate to and from each other.

2. A heel removing machine comprising a base, standards projecting upwardly from the base, a pair of knives vertically movable in said standards, a rack bar depending from the upper knife, a shank depending from the lower knife and provided in its opposite side edges with rack teeth, a pinion interposed between said shank and rack bar, another rack bar disposed adjacent said shank, a pinion interposed between said last-named rack bar and the shank, the standard adjacent the last-named rack bar being provided with an elongated recess, a collar mounted upon said rack bar and movable in said recess, and an expansion spring mounted upon the rack bar between said collar and the bottom of the recess, whereby the knives 75 80 will be returned to their normal position after actuation.

In testimony whereof I have signed my name to this specification in the presence of two subscribing witnesses.

PHILIP BRUNER.
